Primary Examiner — Kendra Leslie Hamilton*Assistant Examiner* — Elizabeth S Struble(74) *Attorney, Agent, or Firm* — Lipsitz & McAllister, LLC(57) **CLAIM**

The ornamental design for a post-surgical shoulder support as shown and described.

DESCRIPTION

FIG. 1 is a front, top and right side perspective view of a post-surgical shoulder support showing the new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front, top and right side perspective view thereof.

In the drawings, the equal-length broken lines depict portions of the post-surgical shoulder support and form no part of the claimed design. In FIG. 8, the broken line showing of a human depicts environmental subject matter only and forms no part of the claimed design. All broken lines form no part of the claim.
